US00D835419S

(12) **United States Design Patent** (10) **Patent No.:** **US D835,419 S**
Lim (45) **Date of Patent:** **** Dec. 11, 2018**

(54) MULTI-HEAD DUAL END COSMETIC APPLICATOR	987,277 A	3/1911	Wright
	1,142,698 A	6/1915	Grove et al.
	1,185,617 A	6/1916	Blaha et al.
	1,190,227 A	7/1916	Fesler
(71) Applicant: HCT GROUP HOLDINGS LIMITED , Central (HK)	1,242,956 A	10/1917	Lewyt
	1,261,502 A	4/1918	Farrows
	1,351,552 A *	8/1920	Bricken B43K 21/08 401/63
(72) Inventor: Cindy Sean Yuei Lim , Santa Monica, CA (US)	1,355,026 A	10/1920	Austin
	1,429,823 A	9/1922	Allison
	1,457,615 A	6/1923	Bunker
	1,480,814 A	1/1924	Bright et al.
	1,486,957 A	3/1924	England
	1,501,835 A	7/1924	Bash
	1,508,306 A	9/1924	Strulson
	1,510,898 A	10/1924	Nikicser
	1,527,052 A	2/1925	McAndrews
	1,563,031 A	11/1925	Jones
	1,586,332 A	5/1926	Vinton
	1,651,355 A	12/1927	Alland
	1,666,116 A	4/1928	Bunnell
	D79,456 S *	9/1929	Coby D19/168
	1,748,491 A	2/1930	May
	1,748,895 A	2/1930	Jordan
	1,831,393 A	11/1931	Pierce, Jr.
	1,864,874 A	6/1932	Voight
	1,889,496 A	11/1932	Priest
	1,899,242 A	2/1933	Mcnab
	1,914,240 A	6/1933	Caldwell
	1,938,442 A	12/1933	Stuart
	1,972,532 A	9/1934	McMillan
	2,104,651 A	1/1938	Hoffman, Jr.
	2,132,943 A	10/1938	Frazier
	2,141,531 A	12/1938	Graham
	2,199,154 A	4/1940	Frohnert
	2,262,753 A	11/1941	Brennan
	D134,797 S	1/1943	Lubkin
	D137,554 S	3/1944	Herb
	2,442,051 A	5/1948	Luscri
	2,485,822 A	10/1949	Goldrich
	2,590,329 A	3/1950	Kromray
	2,533,838 A	12/1950	Ranft
	D161,826 S *	2/1951	Ferber D19/185
	D165,691 S	1/1952	Macomic
	2,584,735 A	2/1952	Pancoast
	2,591,537 A	4/1952	Gordon
	2,622,256 A	12/1952	Vojacek
	2,637,060 A	5/1953	Cowan
	2,637,868 A	5/1953	Hamilton
	2,642,331 A	6/1953	Sprinkle
	2,701,378 A	2/1955	Reinbolt et al.
	2,736,051 A	2/1956	Boodakian
	D179,795 S *	3/1957	Aversa D19/170

CLAIM

The ornamental design for a multi-head dual end cosmetic applicator, as shown and described.

DESCRIPTION

FIG. 1 is a perspective view of a first embodiment of a multi-head dual end cosmetic applicator showing the new

design with an interchangeable head coupled to one end of the multi-head dual end cosmetic applicator;

FIG. 2 is a front elevation view of the multi-head dual end cosmetic applicator of FIG. 1, the back elevation view being identical to the front elevation view;

FIG. 3 is a right side elevation view of the multi-head dual end cosmetic applicator of FIG. 1, the left side elevation view being identical to the right side elevation view;

FIG. 4 is a top plan view of the multi-head dual end cosmetic applicator of FIG. 1;

FIG. 5 is a bottom plan view of the multi-head dual end cosmetic applicator of FIG. 1;

FIG. 6 is a perspective view of a second embodiment of a multi-head dual end cosmetic applicator showing the new design with interchangeable heads coupled to both ends of the multi-head dual end cosmetic applicator;

FIG. 7 is a front elevation view of the multi-head dual end cosmetic applicator of FIG. 6, the back elevation view being identical to the front elevation view;

FIG. 8 is a right side elevation view of the multi-head dual end cosmetic applicator of FIG. 6, the left side elevation view being identical to the right side elevation view;

FIG. 9 is a top plan view of the multi-head dual end cosmetic applicator of FIG. 6;

FIG. 10 is a bottom plan view of the multi-head dual end cosmetic applicator of FIG. 6;

FIG. 11 is a perspective view of a third embodiment of a multi-head dual end cosmetic applicator showing the new design without interchangeable heads coupled to either end of the multi-head dual end cosmetic applicator;

FIG. 12 is a front elevation view of the multi-head dual end cosmetic applicator of FIG. 11;

FIG. 13 is a right side elevation view of the multi-head dual end cosmetic applicator of FIG. 11, the left side elevation view being identical to the right side elevation view;

FIG. 14 is a back elevation view of the multi-head dual end cosmetic applicator of FIG. 11;

FIG. 15 is a top plan view of the multi-head dual end cosmetic applicator of FIG. 11, the bottom plan view being identical to the top plan view;

FIG. 16 is a cross-sectional view of the multi-head dual end cosmetic applicator of FIG. 11;

FIG. 17 is a perspective view of a fourth embodiment of a multi-head dual end cosmetic applicator showing the new design with an interchangeable head coupled to one end of the multi-head dual end cosmetic applicator;

FIG. 18 is a front elevation view of the multi-head dual end cosmetic applicator of FIG. 17;

FIG. 19 is a right side elevation view of the multi-head dual end cosmetic applicator of FIG. 17, the left side elevation view being identical to the right side elevation view;

FIG. 20 is a back elevation view of the multi-head dual end cosmetic applicator of FIG. 17;

FIG. 21 is a top plan view of the multi-head dual end cosmetic applicator of FIG. 17;

FIG. 22 is a bottom plan view of the multi-head dual end cosmetic applicator of FIG. 17;

FIG. 23 is a cross-sectional view of the multi-head dual end cosmetic applicator of FIG. 17;

FIG. 24 is a perspective view of a fifth embodiment of a multi-head dual end cosmetic applicator showing the new design with interchangeable heads coupled to both ends of the multi-head dual end cosmetic applicator;

FIG. 25 is a front elevation view of the multi-head dual end cosmetic applicator of FIG. 24;

FIG. 73 is a top plan view of the multi-head dual end cosmetic applicator of FIG. 70;
FIG. 74 is a bottom plan view of the multi-head dual end cosmetic applicator of FIG. 70;
FIG. 75 is a cross-sectional view of the multi-head dual end cosmetic applicator of FIG. 70;
FIG. 76 is a perspective view of a fourteenth embodiment of a multi-head dual end cosmetic applicator showing the new design with interchangeable heads coupled to both ends of the multi-head dual end cosmetic applicator;
FIG. 77 is a front elevation view of the multi-head dual end cosmetic applicator of FIG. 76, the back elevation view being identical to the front elevation view;
FIG. 78 is a right side elevation view of the multi-head dual end cosmetic applicator of FIG. 76, the left side elevation view being identical to the right side elevation view;
FIG. 79 is a top plan view of the multi-head dual end cosmetic applicator of FIG. 76;
FIG. 80 is a bottom plan view of the multi-head dual end cosmetic applicator of FIG. 76;
FIG. 81 is a cross-sectional view of the multi-head dual end cosmetic applicator of FIG. 76;
FIG. 82 is an enlarged perspective view of a first interchangeable alternative brush head, shown separately for clarity of illustration, that is attachable to either end of the multi-head dual end cosmetic applicator of any of the above embodiments;
FIG. 83 is a front elevation view of the interchangeable head of FIG. 82, the back elevation view being identical to the front elevation view;

FIG. 84 is a right side elevation view of the interchangeable head of the FIG. 82, the left side elevation view being identical to the right side elevation view;
FIG. 85 is a top plan view of the interchangeable head of FIG. 82;
FIG. 86 is a bottom plan view of the interchangeable head of FIG. 82;
FIG. 87 is an enlarged perspective view of a second interchangeable alternative brush head, shown separately for clarity of illustration, that is attachable to either end of the multi-head dual end cosmetic applicator of any of the above embodiments;
FIG. 88 is a front elevation view of the interchangeable head of FIG. 87, the back elevation view, right side elevation view, and left side elevation view being identical to the front elevation view;
FIG. 89 is a top plan view of the interchangeable head of FIG. 87; and,
FIG. 90 is a bottom plan view of the interchangeable head of FIG. 87.
The broken lines in the drawings illustrate portions of the article that form no part of the claim. Further, the broken away symbols in the drawings indicate that any portion of the article beyond what is shown forms no part of the claimed design. The component parts shown in FIGS. 82-90 form part of the fourteen embodiments shown in FIGS. 1-81.
